CHANNEL FOR ELECTRIC CONDUCTORS

Bengt Efraim Legerius, Nykoping, Sweden, assignor to
Telefonaktiebolaget, Stockholm, Sweden

Filed Aug. 2, 1973, Ser. No. 384,881

Claims priority, application Sweden Feb. 2, 1973

Term of patent 14 years

Int. Cl. D13—03

U.S. Cl. D26—1 R

Fig. 1

Fig.2

FIG. 1 is a bottom perspective view of a channel for electric conductors showing my new design.

FIG. 2 is a top perspective view thereof.

The sides of the channel are solid and plain.

I claim:

The ornamental design for a channel for electric conductors, as shown and described.
